HOOK-OFF FOR WELLS

Filed March 11, 1929

Harley H. Markey

INVENTOR

BY Victor J. Evans

ATTORNEY

WITNESS:

UNITED STATES PATENT OFFICE

HARLEY H. MARKEY, OF HOMER, LOUISIANA

HOOK-OFF FOR WELLS

Application filed March 11, 1929. Serial No. 346,203.

This invention relates to new and improved means for attaching and detaching the hooks and pull rods of well rigging and the like.

An object of the invention comprehends the provision of a guide for the pull rod.

Another object of the invention contemplates a detachable element for the pull rod.

A further object of the invention embodies an operating member for the detaching element.

More specifically stated the operating member is provided with a handle whereby the well rod may be disconnected without subjecting the hands to serious injury.

With the above and other objects in view, the invention further consists of the following novel features and details of construction, to be hereinafter more fully described, illustrated in the accompanying drawing and pointed out in the appended claim.

In the drawing:

Figure 1 is a perspective view of the hook and well rod in operating positions.

Figure 2 is a view similar to Figure 1 with the invention in use showing the well rod detached from the hook.

Figure 3 is a top plan view of a portion of the hook or detaching device.

Figure 4 is an elevation of a modified form of connection for the detaching or hook off device.

Figure 5 is a side elevation of the modified form of my invention.

Referring to the drawing in detail wherein like characters of reference denote corresponding parts, the reference characters 10 indicate spaced standards carrying a cross bar or timber 11 to provide a guide for a pull rod 12 passed through an opening 13 therein.

40 A stirrup, generally designated as at 14, is adapted to engage the yoke end 15 thereof with the hook extremity 16 of a reach arm 17.

A rod member 18 is clamped, welded or otherwise secured to the pull rod 12 upon the under side thereof and having one end sufficiently spaced from the adjacent side of the cross bar or timber 11 whereby the pull rod may oscillate to its maximum unrestricted by the presence of said rod member.

50 A U-bolt 19, having the ends thereof passed

through spaced openings 20 in the timber 11, are threaded for engagement with nuts 21 whereby sliding movement of the U-bolt through the openings 20 in the cross bar 11 will be restricted in one direction. Said U-bolt is preferably located beneath the pull rod 12, the purpose of such disposition will be presently apparent in the following description and operation of my invention.

An extension or handle 22, projecting from one end of the U-bolt 19, will provide the means of raising the yoke end of the U-bolt in parallelism with the pull rod 12 from the side of the cross bar 11 adjacent the stirrup 15.

Hook members 23, formed or otherwise provided upon the rod member 18, at spaced intervals in the length thereof, are downwardly and outwardly curved to prevent displacement of the yoke end of the U-bolt 19 when engaged therewith.

In Figure 4 of my drawing I have illustrated a modified form of connection for the U-bolt in the nature of sleeve members 24 arranged at spaced intervals upon the pull rod, after the manner of the hook members 23, and which are provided with open hooks 25 depending therefrom and which are also adapted for selective engagement with the yoke or closed end of the U-bolt 19.

When it is desired to uncouple or otherwise disengage the adjacent ends of the pull rod 12 and reach arm 17, namely, the stirrup 14 and hook 16 therefor, the operator will wait until the pull rod is shifted its utmost or maximum through the opening 13 in the cross bar 11 toward the hook 16. At such time the extension or handle 22 is engaged and depressed to rock the arms of the U-bolt within the openings 20 in the cross bar 11 whereby the closed or yoke end of the U-bolt 19 will be disposed in parallelism with the rod member 18 and pull rod 12 and in the path of movement of the adjacent hook members 23 or 25. Such engagement will restrict sliding action of the pull rod in one direction and after the hook 16 is shifted toward the stirrup 14, the adjacent portion of the pull rod 12 is depressed and said hook will ride out of the 100

yoke or loop 14 to occupy the Figure 2 position and terminate the uncoupling process.

In all previous forms of uncoupling or hook off devices, the stirrup is generally used to hook the well off. This is done by hooking into the stirrup or placing a block between the stirrup and the hook off post.

The modification of my invention shown in Figure 5 of the drawing embodies the following characteristics.

10 A rod member or shaft 26 is preferably fixedly connected, by any suitable means, to a cross bar, not shown, and located in spaced relation to a well rod, such as indicated at 27 and immediately beneath same.

15 An ear 28 of the triangular shape is provided with an enlarged portion 29 upon one side of the base therefor, as shown in dotted lines in Figure 5 of the drawing. One end of the 20 enlarged portion 29 is tapped to accommodate the adjacent threaded end of the shaft 26.

25 A handle member 30, pivotally mounted, as at 31, upon the same side of the ear 28, with relation to the enlarged portion 29, carries a weighted arcuate shaped eccentric 32 having its rounded face serrated or otherwise roughened for biting engagement with the adjacent upper surface of the pull rod 27.

30 By reason of the fact that the enlarged portion 29 of the ear 28 is threadedly engaged with the adjacent end of the shaft 26, a half turn of the enlarged portion upon the shaft in either direction will dispose the lever and eccentric therefor in its respective working 35 positions.

35 When the pull rod 27 is shifted for oscillatory movement toward the cross bar, not shown, that is, after the modified form of hook off device is set up in working position, 40 said rod will travel its limit and upon the slightest retrograde movement, the arcuate shaped face of the eccentric will bitingly engage the adjacent upper surface of the pull rod and force the under side thereof against 45 the upper surface of the enlarged portion 29. The hook upon the extremity of the reach arm will then ride out of the stirrup in the adjacent end of the pull rod as the latter drops or is sprung down.

50 The invention is susceptible of various changes in its form, proportions and minor details of construction, and the right is herein reserved to make such changes as properly fall within the scope of the appended claim.

55 Having thus described the invention, what is claimed is:—

60 A hook-off device for well rods comprising a cross bar, a pull rod slidably mounted thereon, a reach arm, a stirrup carried upon one end of the pull rod for connection with the reach arm, a U-bolt mounted for rocking movement upon the cross bar adjacent the reach rod, hook members carried by and operable in conjunction with the pull rod selec-

tively engaged with the U-bolt to release the stirrup from the reach arm, and a handle for the U-bolt.
